(57) **CLAIM**

We claim the ornamental design for an transitional image for
a portion of a display screen, as shown and described.

DESCRIPTION

FIG. 1 is a front view of the first image of a transitional
image for a portion of a display screen;

FIG. 2 is a front view of the second image thereof; and,
FIG. 3 is a front view of a third image thereof.

The appearance of the transitional image sequentially transi-
tions between the images shown in FIGS. 1-3. The process
or period in which one image transitions to another forms no
part of the claimed design. The broken line drawings of
elements, indicia, and words within the claimed design, and
the portion of a display screen in all views is for illustrative
purpose only and forms no part of the claimed design.
